OR D 731

At No 731.
J. H. Wilson Design for cast iron Monuments
Patented Sept. 18, 1855

Dec. 731

J. H. Wilson of Chesterfield, Ill.
Letters Patent No. 731, Dated Sept 18, 1855.

The schedule referred to in these Letters Patent, and making part of the same —

To all whom it may concern:

Be it known that J. H. Wilson of Chesterfield, Macoupin County, Illinois, have invented or produced, a new, and original design, for a Cast-Iron Monument for graves, and I do hereby declare that the following is a full, and exact description of the same, reference being had to the accompanying drawings, and to the letters of reference marked theron: a. represents a recess for the reception of a miniature likeness of the person, with an inscription written, or printed upon paper, or parchment, or engraved upon metallic plate, or otherwise, and cemented under glass, the whole being protected by a metallic door, which renders it perfectly impervious to moisture, and when the door is closed, nearly so to light. b. represents a locket for hair, which is enclosed, under glass.

c. is a tenon to be set in a mortise of stone, at the head of the grave. The whole is made of cast-iron, except the hinges of the door to the recess, which are of copper, and the hushings, which are wrought iron rods.

The monuments are finished by galvanizing with zinc, or painting, or otherwise. And what I claim as my invention, and desire to secure by Letters Patent, is a design for a cast-iron monument for the head of graves, combining the figures of the Harp, and heart with a recess, for the insertion of a miniature likeness and inscription, and a locket for hair.
